UNITED STATES PATENT OFFICE.

EDWARD H. RIEKE, OF EAST CHICAGO, INDIANA.

ARCH SUPPORT.

Application filed April 9, 1926. Serial No. 100,787.

My invention relates to arch supports, and its principal object is to provide an arch support wherein the arch of the human foot will be supported in correct or natural position and permit the foot to move in the usual manner while walking.

Further, the invention contemplates an arch support which is self-adjusting to the arch of the human foot, allowing the latter to roll or move in a natural manner incident to walking.

Still another object of my invention is to provide an arch support which will adjust itself to the arch rather than adjust the foot to the arch support, as is customary with devices of this character now in use.

It is also an object of the present invention to provide an arch support employing a cushioned floating arch-supporting element which will always effectively engage the arch and produce a maximum pressure on the small bones of the arch and thereby tend to force them back into their normal position to correct the common foot ailment known as "fallen arches."

My invention also contemplates an arch support which in addition to permitting the foot to move in a natural manner and effectively brace or support the arch, may be worn in the shoe without discomfort.

On the drawing—

Fig. 1 is a view of a shoe broken away at one side and illustrating my improved arch support in use;

Fig. 2 is a perspective showing the various elements or units of the device;

Fig. 3 is a view partly in side elevation and partly in perspective;

Fig. 4 is a top plan view;

Fig. 5 is a transverse sectional view of the device.

Fig. 6 is a fragmentary longitudinal sectional view taken on line 6—6 of Fig. 4.

Referring to the drawings in detail where-in corresponding characters of reference denote corresponding parts throughout the several views, the numeral 5 designates a base plate formed of light stout metal and having the outline of the sole of a shoe. The rear or posterior end of the plate is depressed as at 6, to conveniently and comfortably receive the heel of the shoe. The forward or anterior end of the plate is raised or rounded as at 7, to lie under the metatarsal arch of the foot. As illustrated in Fig. 2, the longitudinal edges and the posterior end of

the plate 5 are bent upwardly to produce an angular marginal flange 8, the purpose of which is to strengthen the plate and obviate the cutting of the leather of the shoe.

Arranged above the plate 5 and extending longitudinally of the same is an arch-supporting plate 9 also constructed from light stout metal and having its opposite ends stopped short of the opposite ends of the plate 5. The forward or anterior end of the arch-supporting plate 9 is provided with a semi-circular notch 10, the edge of which coincides with the curve at the inner edge of the raised or rounded anterior part 7. The opposite end of the plate 9 is also provided with a semi-circular recess 11 which coincides with an extension around the depressed posterior end. A leather insole 12 of the same configuration as the plate 5 is disposed upon the upper face of the arch-supporting plate 9 and is secured to the latter by means of rivets or other fastenings 13. By the provision of the notches 10 and 11 the anterior and posterior parts of the insole 12 will conform to the shape of the posterior part 7 and anterior part 6 of the plate 5.

The present invention contemplates mounting the arch-supporting plate 9 for floating movement on the plate 5 to permit the foot to roll or move in the natural manner while walking. That is to say, in walking the foot oscillates and simultaneously shifts back and forth in the shoe. This movement is accomplished by means of an oscillatory and reciprocatory resilient support designated in its entirety at 14. This support 14 is constructed from a blank of sheet metal bent transversely upon itself as at 15, to provide a pair of divergent plates or legs 16 and 17. The support 14 extends transversely of the arch-supporting plate 9 at the crest of the latter, with the plate or leg 16 extending parallel to and contacting with the arch-supporting plate 9 as shown in Fig. 5, and is riveted or otherwise secured to the latter by fastenings 18.

As particularly illustrated in Fig. 2, the leg or plate 17 is longitudinally curved and is adapted for simultaneous rocking and longitudinal movement on the plate 5. Projecting from the plate 5 at the medial arch is a plurality of upstanding pins 19, the latter being arranged in a diagonal line with respect to the longitudinal axis of the plate. Slots 20 are provided in the leg 17 and are disposed in stepped relation to coincide with

- and receive the upstanding pins 9. In order to prevent disengagement of the leg or plate 17 from the pins 19 a leaf spring 21 is supported on the intermediate post or pin 19 with its ends bearing against the ends of the leg 17. This intermediate pin or post 19 is slightly larger in diameter than the remaining pins and is provided with a vertical bore 22 receiving a tapered fastening 23, the latter passing through a central opening 24 in the leaf spring 21. In order to secure the tapered fastening 23 within this post 19 the latter is squeezed or crimped as illustrated in Fig. 5.
- 15 A plurality of aligned coil springs 25 is interposed between the legs 16 and 17 to cushion the arch-supporting plate 9 and press the same into the arch of the human foot. In connection with these springs 25 it will be observed that any practical number of the same may be employed and that they will be of a potential strength to withstand the weight of the person using the device. It will also be observed that the coil springs 25 are connected to the legs 16 and 17 without the employment of rivets or other separable fastenings. Each of the legs is formed with a pair of transversely aligned, inwardly directed, tubular bosses 26 which project into the endmost convolutions of the springs 25. These tubular bosses are formed with spaced circumferential incisions 27, permitting the bosses to be crimped around the endmost convolutions of the springs as designated at 27.
- 30 Furthermore, these springs must be so arranged as to attain a perfect balance for the foot while the latter tips longitudinally and transversely during walking.
- 40 Due to the tendency of the human foot to spread or move to one side during walking, there will be a tendency of the arch-supporting plate 9 to move laterally when it is under compression. This objection is obviated by arranging bearing balls 28 in a longitudinal track or raceway 29 at one side of the posterior part 7 of the plate 5. A longitudinal recess or depression 30 is formed in the arch-supporting plate 9 in vertical alignment with the bearing balls 28 and engages the latter as the arch-supporting plate comes in contact with the base plate 5.
- 55 A resilient angularly disposed plate 31 is secured to the under face of the posterior end 6. This resilient plate 31 acts as a cushion or shock absorber to the heel as the latter strikes the ground. However, this resilient plate 31 may be dispensed with if desired.
- 60 One of the difficulties of the present rigid arch support is that it cracks or breaks at the medial arch point. This objection is overcome by my invention due to the fact that the medial arch point of the arch support is cushioned by the coil springs 25.
- 65 Having thus described my invention,

what I claim and desire to secure by Letters Patent is:—

1. An arch support including a base, an arch-supporting plate carried thereby and supported thereon for simultaneous, rocking and longitudinal movements. 70
2. An arch support comprising a base plate, an arch-supporting plate arranged thereon, a rocking and sliding member interposed between the base plate and arch plate and fixed to the latter, and a flexible top covering for the arch plate. 75
3. An arch comprising an arch-supporting plate, a resilient plate extending transversely of the crest of the arch-supporting plate 80 and attached to the latter, and means for mounting the resilient plate for longitudinal and rocking motions to permit the human foot to move naturally while the arch thereof is supported. 85
4. An arch support comprising a base plate, an arch-supporting plate arranged above the latter, a rocking and sliding support secured to the arch-supporting plate and resting upon the base plate. 90
5. An arch support including a base, an arch-supporting plate arranged above the latter, a pair of relatively narrow divergent plates interposed between the base plate and arch-supporting plate and extending 95 transversely across the crest of the latter, expansible elements interposed between the divergent plates, one of such plates being longitudinally bowed and rockably and slidably mounted on the base plate. 100
6. An arch support including a base, an arch-supporting plate arranged above the latter, a pair of relatively narrow divergent plates interposed between the base plate and arch-supporting plate and extending transversely across the crest of the latter, expansible elements interposed between the divergent plates, one of such plates being longitudinally bowed and rockably and slidably mounted on the base plate, and split 105 bosses on the plates and crimped to the expansible elements. 110
7. An arch support comprising a base, an arch-supporting plate arranged above the latter, a rocking and sliding member carried by the under face of the arch-supporting plate and resting upon the base plate, operative connections between the rocking and sliding member and base plate, and expansible means interposed between the base 115 plate and arch-supporting plate. 120
8. An arch support including a base plate having its posterior and anterior ends shaped to conform to the posterior and anterior arches of the human foot, an oscillatory slideable arch supporting plate mounted on the base plate, a protective pad attached to the arch-supporting plate and accommodating itself to the posterior and anterior ends of the base plate, and resilient elements 130

interposed between the base plate and arch-supporting plate.

9. An arch support including a base plate, an arch-supporting plate mounted thereon for oscillatory movement, cushioning means between the base plate and arch-supporting plate and arranged to exert pressure at the crest of the arch-supporting plate to resiliently support the latter and to prevent breaking of the said arch-supporting plate at the crest.

10. An arch support comprising a base plate, a longitudinally bowed rocking element mounted on the base plate and capable of a slight longitudinal movement thereon, and an arch supporting plate unattached to the base plate but attached to the rocking element.

11. In an arch support, a fixed plate, an arch supporting plate, a resilient plate transversely secured to the arch supporting plate and having a turned under portion with a rocking face and adapted to rock on the fixed plate, and cushioning means between the arch supporting plate and said turned under portion. 20 25

12. The arch support of claim 11, with cushioning means for the heel and a metatarsal pad adapted to support the anterior portion of the foot as the turned under portion rocks forward to place the weight toward the anterior portion of the foot. 30

In witness whereof, I hereunto subscribe my name this 27th day of March, 1926.

EDWARD H. RIEKE.
